Attys.

Patented Mar. 12, 1929.

UNITED STATES PATENT OFFICE.

ANTHONY PAPINI, OF LEONIA, NEW JERSEY, ASSIGNOR TO PERCY W. VALENTINE, OF CAMBRIDGE, MASSACHUSETTS.

RADIANT-HEAT PROJECTOR.

Application filed November 21, 1927. Serial No. 234,687.

The primary object of the present invention is to provide an electric heater capable of projecting a concentrated beam of heat rays emanating from an electric heating unit, 5 and being compact and small in external dimensions. My problem in this invention has been to produce such a projector of dimensions sufficiently small to enable it to be used in situations where heaters of the common 10 "sunbowl" type cannot be used on account of their size and the diffusion of the beams which they project, and at the same time to develop a large quantity of heat and direct a beam of radiant heat rays in such concentration that a high temperature may be maintained 15 in the path of the beam at a long distance from the heat source, without causing the heat rays to converge at a distant focus, but maintaining a practicable minimum of dispersion of the rays. As an example of the 20 uses which the projector herein disclosed is intended and adapted to serve, I would refer to the patent of P. W. Valentine, No. 1,583,757, dated May 4, 1926, which shows a sewing machine using a hot waxed thread and provided with a heat projector arranged to throw a beam of heat rays on the thread in its passage from the wax pot to the stitch forming point in order to prevent premature 25 chilling and stiffening of the wax in the thread. For this use small dimensions in the projector and high concentration of the beam are highly desirable. But the apparatus of course is adapted and intended to serve a 30 variety of other uses in which similar concentration of heat rays in a small area to supply a sufficient limited quantity of heat from a distant heat source is desired.

In the accomplishment of my object I have 35 devised a new form of reflector in association with a heating unit and a new combination of heating unit with reflector and coupling means, together with new details of construction and arrangement of the various parts of the device, all contributing to the final result 40 of compactness and simplicity of structure and the desired concentration of reflected rays. The invention consists in these and related novel features and improvements, as 45 will now be explained in connection with a detailed description of the present preferred embodiment of the invention.

Referring to the drawings,—

Fig. 1 is an axial or longitudinal section of

a heat projector embodying my invention in 55 its preferred form;

Fig. 2 is an elevation as seen from the right of Fig. 1; this view showing the front of the projector;

Fig. 3 is a perspective view partly broken 60 away and shown in section of the cover fitting;

Fig. 4 is a perspective view of the associated clamping piece and confining bands disassembled for clearer illustration; 65

Fig. 5 is a perspective view of an insulating disk provided to separate the leads from the heating element.

Like reference characters designate the 70 same parts wherever they occur.

The heating element is a coil *a* of high resistance wire of any character suitable for this purpose, wound about the outer surface of a cylindrical sleeve or muffle *b* having a helical groove to position the turns of the 75 coil element and having also a base flange *c*. Such base flange cooperates with the clamping piece or thimble *d* to position and secure the reflector *e*, and it is connected to the clamping piece by a single bolt *f*, passing 80 through aligned holes in the contiguous end walls of the muffle and clamping piece, and a nut *g* threaded on one end of the bolt.

One end of the heating element is passed 85 through a notch *h* in the outer end of the muffle and through the central passage or bore of the muffle to the bolt *f*, with which it is engaged in electrically conductive connection. The lead wire *i* for coupling this terminal of the heating unit with the source of 90 power is brought into the open central recess of the clamping piece and is there held in electrical connection with the bolt *f* by the nut *g*, under which the terminal of the conductor is placed. The opposite terminal of 95 the coil passes through aligned holes *j* and *k* in the muffle base *c* and in the end wall of the clamping piece, passing into the recess in the latter, and being there joined to the opposite lead conductor *l*. An insulating separator 100 disk *m* is fitted to the recess in the clamping piece, it being held therein by frictional peripheral contact with the walls of the recess, and has opposite notches *n* to receive the bare leading in conductors, the body of 105 the disk between these notches holding the bare conductors apart.

The reflector *e* embodies several features

of the invention. Its first important characteristic is its form, which is conical in part and approximately parabolic in another part. The conical part, which is preferably tapered at an angle of approximately 45° with the axis, extends from a point p near the base flange of the muffle to a plane q approximately midway between the ends of the heating element, and from q to the plane r the reflector is curved smoothly inward from the extension of the conical surface, conforming accurately or approximately to a parabola of which the focus is in the axis of the reflector and the surface is tangent to the conical surface. At its larger or base end the reflector is formed with a cylindrical zone s , a bead t and a flange u to support and confine the band v of a guard. The smaller or apex end of the reflector is formed with a cylindrical part w of a length and internal diameter conforming approximately to the length and diameter of the muffle base c , and with an in-turned flange a adapted to overlap the end of the flange c and be clamped between the latter and the clamping piece, when these parts are drawn together by screwing up the bolt and nut f, g .

Without intending to limit my protection exclusively to the specific proportions of the reflector herein disclosed, but claiming all novelty and advantage in such proportions, I would say that the length of the reflector is approximately equal to that of the heating element; that the diameter of the reflector at its smaller end is approximately twice the diameter of the coil, and its diameter at the largest end of the conical portion is about five times that of the coil, while its diameter at the base is about six times that of the coil. Using a coil 2" long and from $\frac{1}{2}$ " to $\frac{5}{8}$ " in diameter, these proportions give a projector which is small and compact and is adapted to project the reflecting heat rays with a high degree of concentration and far less dispersion than the parabolic reflectors commonly used with the heat projectors designed for domestic heating purposes. In particular, the contraction at the larger end of the reflector caused by its curvature in the zone from q to r , reflects many of the rays with convergence toward the axial line, thereby obtaining a heat concentration in the central part of the beam which goes far to compensate, in high temperature effect, for the unavoidable dispersion of direct rays from the heating unit and of part of the rays reflected from the conical portion of the reflector. This form of reflector gives the maximum practicable concentration of rays from a heating unit which necessarily must have great length and substantial diameter in order to generate the amount of heat required.

The guard previously referred to consists of wires or bars y secured at one end to the

band v , preferably by being passed from the outside through holes and headed over or soldered on the inside of the band, and being curved to pass around the end of the reflector and thence extended to a common meeting point in the axis of the reflector. They may be there joined by any suitable means, as by welding, or by connection with a coupling z of known character as shown.

The device is completed by a cover member a' which in this instance is a sleeve surrounding the clamping member d and contracted to provide an end wall a^2 overlying the latter and a narrow orifice a^3 for receiving the leading in conductors. It is secured to the clamping member by screws b' passing through holes in the opposite sides of the cover and each screwed into the half of a divided ring or collar c' which occupies a groove d' in the clamping member and distributes the pressure of the screw thereon. The cover in the form here illustrated is designed for a projector adapted to be suspended by the electric coil or cable which supplies the current, but it will be understood that the cover may be otherwise formed in particulars well known by the art to adapt it for mounting on a standard or in a clamp of any suitable sort by which it may be affixed to a part of a machine or other support.

The several parts of this apparatus may be made of the materials usual in the art. Thus the muffle, clamping member, cover and insulating disk are of insulating material, preferably Java, although other suitable materials may be used, the reflector preferably of sheet copper spun or pressed by dies to the prescribed shape, the screws f and b' , bands c' and v , and guard wires y of steel or other suitable metal.

What I claim and desire to secure by Letters Patent is:

1. In a heat projector, a reflector adapted to be coaxially mounted with respect to a heating element and having a conical portion for surrounding part of the heating element, and a substantially parabolic portion for surrounding another part of the element.

2. In a heat projector, a reflector adapted to be mounted coaxially with respect to a heating element and surrounding the same, the parts of the reflector of smaller diameter being conical and the parts of larger diameter being substantially parabolic.

3. A heat projector consisting of a helically coiled electric heating element and a reflector mounted coaxially with respect to said element and surrounding the same, the parts of the reflector of smaller diameter being conical and the parts of larger diameter being substantially parabolic, the junction between such conical and parabolic parts being in a plane substantially midway of the axial length of the heating element.

4. A heat projector comprising a helically

- coiled electric heating element, a reflector surrounding said element coaxially and being substantially equal in axial length thereto, the reflector being conical in form from its smaller end for approximately half its axial length and its larger portion being formed to approximate a paraboloid tangent to the conical portion.
5. A heat projector comprising a helically coiled electric heating element, a reflector surrounding said element coaxially and being substantially equal in axial length thereto, the reflector being conical in form from its smaller end for approximately half its axial length and its larger portion being formed to approximate a paraboloid tangent to the conical portion, the larger end portion of the reflector being formed with a cylindrical guard supporting zone tangent to such paraboloid.
10. A heat projector comprising a helical heating unit and a reflector coaxially surrounding said element, the reflector being conical for approximately half its length adjacent to its smaller end and being approximately parabolic for the remainder of its length, and the reflector and heating element having substantially the following proportions: equal axial length, ratio of coil diameter to reflector diameters, approximately one to two at the smaller end of the reflector, one to five at the plane of junction between the conical and parabolic portions, and one to six at the larger end of the reflector.
15. A heat projector comprising a tubular supporting muffle having a flange at one end, an electric heating element coiled helically around said muffle from a point near the flange to a point near the opposite end of the muffle, a reflector formed at its smaller end to surround said flange and with an inturned lip overlying the outer end of the flange, and having an enlarging taper therefrom, a clamping piece contiguous to the outer end of said base flange overlying the inturned lip of the reflector, and means for securing the clamping member and muffle together so as to grip the reflector lip between them.
20. A heat projector comprising a support for an electric heating element, a clamping member arranged in end to end relation to said support, a central bolt for securing said parts together, a reflector surrounding said support and having a terminal lip arranged to enter between the contiguous parts of the support and clamping member, a cover formed to enclose said clamping member, and fastening means for mounting the cover on the clamping member.
25. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and means for securing the cover to the clamping member.
30. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
35. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
40. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
45. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
50. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
55. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
60. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.
65. An electric heater comprising a tubular support for a coiled electric heating unit having a base wall, a complemental clamping member adapted to be placed contiguous to said wall in general alinement with the support, said clamping member having a central recess in its side opposite to the support and a wall adjacent to the support, a single bolt passing through the contiguous end walls of the support and clamping member for holding them together, a cover formed to embrace said clamping member and having an orifice opening into the recess in the clamping member for reception of electrical conductors, the clamping member having an encircling groove within the cover, and screws mounted in the cover and passing into said groove to secure the cover upon the clamping member.

which said connecting screw extends and is adapted to serve as a binding post for an electrical conductor, and the clamping member having also a perforation alined with the perforation in the flange of the coil support, opening into said recess and adapted to receive the second terminal of the heating coil or a lead wire connected therewith.

13. An electric heater comprising a tubular support having a transverse wall and outstanding flange at one end, the wall and flange being perforated both inside and outside of the tube, an electric heating element wound about said support extending at one side into the bore of the tube to the perforation therein, its other end being passed through the perforation in the outer flange, a clamping member having a wall contiguous to said end wall, perforated in alinement with the interior perforation of the support, a clamp screw passing through the alined perforations holding

the members together and serving as a binding screw for one terminal of the heating coil, the clamping member having a recess at the opposite side of the end wall thereof into which said connecting screw extends and is adapted to serve as a binding post for an electrical conductor, and the clamping member having also a perforation alined with the perforation in the flange of the coil support, opening into said recess and adapted to receive the second terminal of the heating coil or a lead wire connected therewith, and a separator disk fitted in the recess of the clamping member having separated notches to receive electrical conductors leading, respectively, to the said connecting screw and to the opposite terminal of the heating coil.

In testimony whereof I have affixed my signature.

ANTHONY PAPINI.
